LINE VALVE

Ladd M. Adams, Norman, Okla., assignor to Balon Corporation, Oklahoma City, Okla., a corporation of Oklahoma

Original design application Aug. 26, 1966, Ser. No. 3,597, now Patent No. 207,830, dated May 30, 1967. Divided and this application Feb. 7, 1967, Ser. No. 7,336

Term of patent 14 years

(Cl. D23—38)

FIG. 1 is a perspective view of a line valve, showing my novel design.

FIG. 2 is an end view thereof.

FIG. 3 is a side view thereof.

FIG. 4 is a bottom view thereof.

FIG. 5 is a top plan view thereof.

This is a division of design application Ser. No. D. 3,597, filed Aug. 26, 1966, now Design Patent No. D. 207,830.

The fragmentary broken line representation of a handle in FIGS. 1 and 3 is for purposes of illustration only.

I claim:

The ornamental design for a line valve, as shown and described.
